UNITED STATES PATENT OFFICE

HUGH J. MONSON, OF LAKWOOD, OHIO, ASSIGNOR TO DELCO REMY CORPORATION, OF DAYTON, OHIO, A CORPORATION OF DELAWARE

HEAD LAMP FOR AUTOMOBILES

Application filed April 14, 1927. Serial No. 183,680.

This invention relates generally to headlamps for automobiles, and more particularly to the manner of connecting the door or front of the lamp to the body of the same, the object being to provide an exceedingly simple and efficient form of fastening means which will compensate for variations in manufacture and will maintain all of the parts in close sealed relation and avoid rattling.

10 In a large number of headlamps in general use at the present time the door and body are connected by means of a hook or lug engaging the door and lamp body at the top of the headlamp and a screw engaging the 15 nut at the bottom.

It is necessary in headlamp construction to provide an effective seal to exclude moisture, dust and air from the silver plated reflector and in most of the headlamps in common use there are such variations in the manufacture of the various parts that considerable attention must be given to compensate for these variations and produce an effective seal for the reflector.

25 In some cases headlamps having the so-called hook-on type of door construction, a cork seal is employed for two purposes, first to seal the reflector and secondly due to its resiliency to take up the manufacturing variations but frequently these variations are of such magnitude that the cork in itself is not capable of producing an effective seal at all times and it is therefore desirable to provide additional means of compensation so that 30 35 at no time will the reflector seal become inefficient.

The object of the present invention, therefore, is to provide a door connecting means in which springs are employed to aid and maintain a competent seal and another object is to so secure the sealing means that the same does not become impaired or deranged in applying the door to the body of the lamp.

40 Another object is to provide novel means for securing the glass in the door frame so that the glass will be securely held even when the frame is disconnected from the lamp body.

45 Where spring means have been employed in the past, the location of the door lug at the top has been placed so far towards the front

of the door that after the door has been removed it was difficult to reassemble it to the body and engage the lug in the slot due to the fact that the position of the lug was obscured during the assembling operation.

55 It is, therefore, one object of this invention to so design the various features as to bring the door lug as close as possible to the rear edge of the door so that when the door is assembled to the lamp body the engagement of this lug with the slot in the body of the lamp is clearly visible.

With these various objects in view the invention consists in the various novel features of construction and in the manner of combining or arranging the same all of which will be fully described hereinafter and set forth in the appended claims.

55 In the drawings forming a part of this specification Fig. 1 is a vertical sectional view of an automobile headlamp embodying the novel features of my invention; Fig. 2 is a face view of the lamp with the door removed therefrom; Fig. 3 is a rear or inner face view of the door and lens or glass; Fig. 4 is a sectional plan view taken on the line 4—4 of Fig. 1; Fig. 5 is a detail sectional view illustrating the spring clamps for holding the glass or lens in the door frame and also the manner of connecting the reflector to the lamp body; and Fig. 6 is a detail view of a modified form of spring clamp.

70 In the practical embodiment of my invention I employ a lamp body or shell 10 which may be of any desired shape, the front circular edge thereof being turned inwardly as shown at 11, and the reflector 12 is secured to this inwardly turned edge by means of screws 13, the reflector being formed with an annular seat or groove 15 to receive the cork 75 sealing ring 16.

75 At the top of the reflector an outwardly projecting lip 17 is punched and contacts with the cork packing or sealing ring 16 and holds the same securely seated in the groove or seat 15 and prevents any movement of the ring at the top of the reflector when the door is applied. This is very important as heretofore in hooking the door on at the top and bringing the same down to a vertical closed posi- 80 85 90 95 100

tion a bending or dislocating strain has been applied to the upper outer edge of the cork ring with the result that frequently the inner or rear edge of said cork sealing ring has been 5 sufficiently displaced from its seat on the reflector to impair the seal at that point. By means of the lip or lug 17 this is entirely avoided as the rear inner end of the cork ring is firmly held in place, and all danger 10 of bending or dislocating the same is avoided.

The door or frame 18 is circular in form and channeled as shown, the rear edge being rolled back as indicated at 18^a. The glass 19 fits snugly into the circular frame 15 as shown and is held in place by means of spring clips 20 comprising a long leg 20^a which extends down into the rolled edge 18^a, and a shorter leg 20^b arranged at an angle to the leg 20^a and terminating in a hook 20^c which engages the outer edge of the glass. At the juncture of the legs 20^a and 20^b there is formed a projection 20^d which fits into the groove or seat 18^d of the door or frame 18. These spring clamps securely 25 hold the glass in place, and due to their shape and resiliency maintain their position in the door frame, but if desired indentations can be produced in the rolled-in edge 18^a or a drop of solder may be employed to 30 connect the clamps to the door frame.

In Fig. 6 I have shown the clamp formed of spring wire and comprising the section 21^c which engages the edge of the glass, the protruding portions 21^a which fit into the 35 groove and the members 21^d which are made slightly divergent so as to be readily inserted in the channeled ring, and then by forcing these members towards each other the sharp ends 21^e are caused to bite into the in- 40 rolled edge 18^a thus securely locking the clamps to the ring.

The door is secured to the lamp body at the top by means of a lug 22 and at the bottom by means of a screw 23. The lug 22 45 is angular in form as shown, one portion thereof fitting into the rolled edge 18^a of the door frame while the other member thereof extends inwardly as shown. This inwardly projecting portion of the lug is adapted to 50 pass into the opening 24 produced in the top of the lamp body adjacent the front edge thereof.

Engaging the lug 22 is a spring actuated plate 25 which extends partially across the 55 opening 24 and bears against the lug 22. This plate 25 is bent in the shape indicated in Fig. 1 of the drawings and is partly within the lamp body and partly without. A coil spring 26 is held between the inrolled 60 edge 11 of the lamp body and the inwardly projecting portion 25^a of the plate 25 and whereby pressure is applied to the plate so that tension is always exerted upon the door through the lug 22 tending to force the 65 same rearwardly. This not only holds the

door securely but also firmly holds the glass into contact with the sealing ring 16 so that the seal is completed and the parts prevented from rattling.

The lug 22 is placed so far towards the 70 rear edge of the door frame that it can be readily inserted in the opening 24 and once the lug is so inserted the spring pressure of the plate 25 holds the same in its proper position. The plate 25 being turned back and 75 contacting with the top of the lamp body and having some width is prevented from turning or twisting.

As the front of the lamp is connected to the lamp body at the top and then brought 80 down to a vertical position for the purpose of securing the bottom, the lip 17 punched from the reflector and engaging the top edge of the packing ring 16 will hold said ring firmly seated and will prevent any tendency 85 to tilt the same.

The screw 23 passes through a glass positioning clamp 27 and engages a clevis 28. The glass 19 is formed with a notch 19^a at the center of the bottom edge and the positioning clamp 27 is secured in the glass carrying frame 18 at the bottom thereof being rigidly connected thereto and the inner end 90 of this positioning clip is of such size and is bent as shown at 27^a so as to fit into the 95 notch 19^a. This insures the correct placing of the glass in the frame which is important when the glass is fluted or prismatic for the purpose of giving direction to the beam of light.

The head of the screw 23 fits into the countersunk hole in the frame 18 and the inner threaded end engages the forward end of the clevis 28 which is essentially rectangular in shape, the parallel rearwardly extending lugs thereof passing through openings produced in the inturned edge of the body and a coil spring 29 is held between the rear member of this clevis and the inturned edge 11, as most clearly shown in Fig. 4. The rear 110 side of the clevis is punched out as shown at 28^a and the inturned edge 11 is also punched out as indicated at 11^a for the purpose of positioning the spring 29. At the same time an opening is provided for the entrance of 115 the inner end of the bolt 23. The side members of the clevis frame are also provided with shoulders 28^b which limit the rearward movement of the clevis. The clevis being in the form of a substantially rectangular frame and the side members thereof passing through the openings in the edge 11, all danger of turning is prevented.

The bolt 23 is undercut, as indicated at 23^a so that if desired the bolt can be turned so as 120 to be entirely disengaged from the clevis 28 but will still remain carried by the door frame. In this manner it is possible to disconnect the door frame without removing the bolt from the frame and consequently the 125 130

danger of loss of the bolt is avoided. When the bolt 23 is screwed into engagement with the clevis spring pressure is applied to the bottom of the door frame through the clevis 5 to which the bolt is connected and this pressure will be exerted at all times, the same as the spring pressure is being exerted upon the lug at the upper end by means of the spring actuated plate.

10 It will thus be seen that I provide for the quick and easy attachment of the door frame to the lamp body and at the same time maintain spring pressure thereon so that rattling is avoided and a perfect seal maintained at 15 all times.

Having thus described my invention, what I claim is:—

1. In a lamp, a body portion and a glass carrying frame, spring pressed means in the 20 top of the body for securing the frame to the body at that point, a screw passing through the bottom of the frame, a rectangular shaped clevis located in the body at the lower side thereof, a spring arranged within said clevis 25 and contacting with the clevis and the in-turned edge of the body portion, the forward member of said clevis being threaded and engaged by the screw carried by the frame for the purpose of securing the glass carrying frame to the body at that point.

2. In a lamp, a body portion having in-turned forward edges, a glass carrying frame the glass of which is provided with a radial notch, a clip carried by the frame and fitting 35 into said notch, a bolt carried by the frame having a reduced portion passing through the clip, a rectangular shaped clevis positioned in the in-turned edge of the body portion, a spring positioned between the rear side of 40 said clevis and the in-turned edge of the body, the threaded end of the bolt engaging the threaded forward side of the clevis, an inwardly projecting lug carried at the top side of the frame, the body having an opening 45 in the top thereof and through which the lug passes and a spring actuated plate positioned within the body portion and having its end extending rearwardly over the top of the body portion and engaging the lug.

50 In testimony whereof, I hereunto affix my signature.

HUGH J. MONSON.
